UNITED STATES PATENT OFFICE.

CHARLES BERG, OF NEW YORK, N. Y.

DESIGN FOR A MOTOR-BUS.

47,211.

Specification for Design.

Patented Apr. 13, 1915.

Application filed December 19, 1913. Serial No. 807,795. Term of patent 7 years.

To all whom it may concern:

Be it known that I, CHARLES BERG, citizen of the United States, and resident of New York, in the county of New York and State of New York, have invented a certain new, original, and ornamental Design for a Motor-Bus, of which the following is a specification.

The figure is a vertical elevation of a motor bus showing my new design equipped for summer service.

Copies of this patent may be obtained for five cents each, by addressing the "Commissioner of Patents, Washington, D. C."

I claim:

The ornamental design for a motor bus as shown.

Signed at New York in the county of New York and State of New York this 16th day of December A. D. 1913.

CHARLES BERG.
